SIGNALING DEVICE

Application filed November 11, 1929. Serial No. 406,211.

This invention relates to signaling devices for use on vehicles, motor boats and elsewhere to give warning of an intended change in the direction of driving or of an intended stop, and it has for its object the production of a signaling device for the said purpose which shall be inconspicuous or substantially invisible when it is displaying no signal but which shall, when in operation, cause its signaling member to be distinctly displayed so as to be visible from substantially all directions. Further objects of the invention, which will be herein disclosed as applied to an automobile, are to produce a signaling device of the character stated which shall be dependable in use, simple and inexpensive in its construction and easily applied either as stock equipment of a new car or as an attachment to a car already in use; to provide means readily accessible to the hand of the driver of the vehicle for setting the signal to indicate either a right or left hand turn, and means associated with the brake pedal for setting the signaling device to indicate a stop; to provide connections with the intake manifold of the engine cylinder for producing a suction upon the signal operating means whereby the latter is operated automatically from said manifold, and to provide means for illuminating the device so that the signaling member thereof will be conspicuously displayed at night.

While signaling devices for accomplishing the above stated objects may be embodied in various specific forms, that shown in the accompanying drawings is our preferred embodiment, although it is to be understood that the claims appearing herewith are not intended to be limited to the specific structure shown any farther than is required by their express terms.

In the accompanying drawings, Fig. 1 shows a front elevation of a side portion of an automobile equipped with our invention, the signaling member being shown in full lines to indicate a right hand turn and in dotted lines to indicate both a left hand turn and stop, part of the hood being broken away to show the engine manifold and its connection with the signaling device; Fig. 2 is a

side elevation of the front post of the vehicle body at the left of the driver's seat, said figure also showing the signaling device attached to the front face of said post; Fig. 3 is a transverse section taken horizontally through Fig. 2 on the line 3—3, as indicated; Fig. 4 is a vertical longitudinal section through the signaling device and its operating and controlling means, the same being taken on the lines 4—4 of Fig. 5 and 4^a—4^a of Fig. 6 and looking in the direction of the arrows, the signaling member, which is partly broken away, being shown in full lines where it is in its normal or idle position and in dotted lines where it is in its other positions; Fig. 5 is a view, partly in section and partly in elevation, taken on the line 5—5 of Fig. 4 and looking toward the right, as indicated; Fig. 6 is a sectional view taken horizontally through Fig. 4 on the line 6—6 and looking downwardly, as indicated; Fig. 7 is a sectional view taken vertically through the valve block on the line 7—7 of Fig. 6 and looking in the direction of the arrows; Fig. 8 is a sectional view, similar to Fig. 7, but taken on the line 8—8 of Fig. 6; Figs. 9 and 10 are, respectively, side and edge elevations of one of the dogs for controlling the signaling member; Figs. 11 and 12 are, respectively, side and edge elevations of the other dog for controlling the positions of the signaling member; Fig. 13 is a side elevation of a segmental element connected with the signaling member which cooperates with the dog of Figs. 9 and 10; Fig. 14 is a vertical sectional view on the line 14—14 of Fig. 13 looking toward the left, as indicated; Figs. 15 and 16 are views, corresponding to Figs. 13 and 14, showing the other segmental element connected with the signaling member and cooperating with the dog shown in Figs. 11 and 12, Fig. 16 being taken on the line 16—16 of Fig. 15; Fig. 17 is an insulating member carried by the segmental element shown in Fig. 15; Fig. 18 is a sectional view taken on the line 18—18 of Fig. 4; Fig. 19 is an enlarged sectional view taken through the signaling member on the line 19—19 in Fig. 4; Fig. 20 shows a portion of the rear side of the instrument board having the se- 100

lecting devices for controlling the signaling member mounted thereon; Fig. 21 is, in part, a sectional view taken on the line 21—21 of Fig. 20, said view also showing some of the connections operated by said selecting devices; Fig. 22 is a diagrammatic view showing the brake pedal and some of the connections between the same and the signaling device whereby the latter is controlled by said pedal, and Fig. 23 is a view taken on the line 23—23 of Fig. 4, showing the rocking plate for controlling the various valves.

As will be seen from Figs. 1, 2 and 3, the signaling member 20 is pivoted at 21 in a suitable box or casing 22 which is connected to that front post 23 of the automobile body which is at the left hand side of the driver of the automobile. As therein shown, this box or casing is attached to said post on its front side where it is inconspicuous, and is invisible from the rear of the machine. In applying my invention to cars already built, this is the preferred location of the signaling device; but when the latter is made a part of the regular equipment of the vehicle, it is preferable to have the casing 22 embedded within the said front post in its left hand face, as is indicated by the dotted lines in Fig. 3.

The signaling member 20 is an elongated box-like structure, the front and rear walls of which are composed of suitable transparent material, such as glass or celluloid, as indicated in Fig. 19 at 20^a and 20^b. Within the box-like signaling member is an electric lamp 20^c, controlled, as hereinafter specified, in such a manner as to illuminate the signaling member when it is in any of its display positions. The signaling member 20 is attached at its lower end to fingers 24 which project upwardly from segmental controlling elements 25 and 25^a, these elements being shown in detail in Figs. 13 to 16, inclusive. The said elements are mounted upon a horizontal shaft 26 which is supported at its ends in side plates 27. Also mounted upon the shaft 26, and secured to and between the elements 25 and 25^a, is a gear segment 28, which meshes with the operating rack 29, the latter being reciprocated in a vertical direction by means hereinafter described. Each of the elements 25 and 25^a is formed on two radii, as shown, so as to provide a hook-like projection at 30 and 30^a, respectively, the projection 30 on the segment 25 being farther advanced toward the right than is the corresponding projection 30^a on the other segment. These projections cooperate with the dogs shown in Figs. 9 to 12 and form stops determining the extent of rotation of the gear segment 28 and the signaling member 20 when moved by the rack 29. These dogs, designated 31 and 31^a, respectively, are journaled upon a transverse shaft or pin 32 which is supported within the side plates 27, and they are each

provided with a laterally projecting nose 33, 32^a, the latter each having a rounded surface 33 in the plane of the respective elements 25 and 25^a and adapted to engage the hook-like projections 30 and 30^a thereon to arrest the rotative movement of the gear segment 28 and the movement of the signaling member 20. The dogs 31 and 31^a are independently operable from means within convenient reach and control of the driver of the machine. While various devices may be satisfactorily employed, we have chosen to show the pivoted levers of Figs. 20 and 21. Referring to these figures, 34 represents a portion of the instrument board of the automobile, at the inner face of which there is attached a plate 35 supporting pivoted levers 36 and 37, the levers extending through the instrument board and into the automobile body within convenient reach of the driver. The lever 36 is shown in its normal position, while the lever 37 is shown tilted upwardly at its rear or operating end and downwardly at the end in front of the instrument board. Each of these levers is connected, through a rod 38 and a rocking lever 39 to a vertically extending rod 40. The connections just referred to are shown in the sectional view, Fig. 4, and, in part, in Fig. 18. From the latter view it will be seen that there are two of the pivoted levers 39 to which the rods 40 are connected. These rods are extended upwardly through suitable packing glands 41 in the valve block 42 and into position for lifting ball valves in said valve block, all as will be described hereinafter. Upon each of the rods 40 there is a head or enlargement 43 upon which rests the lower end of other upwardly extending rods 44. There are two of these rods 44, one for each of the levers 36 and 37 on the instrument board, and they are connected at their upper ends with the dogs 31 and 31^a, respectively. From this it will be understood that when one of the levers 36 or 37 is lifted by the operator the corresponding rod 44 will likewise be lifted to turn the respective dog 31, 31^a, into position to bring its nose 33 into the path of the hook-like projection 30, 30^a, of the elements 25, 25^a. These dogs are thus set to determine the extent of movement of the signaling member 20 and the character of signal given thereby.

The rack 29 for turning the gear segment 28 is suitably guided at its upper end and it is reciprocated by a piston 45 within a cylinder 46. To the upper end of the cylinder there is connected a tubular member 47 which is a screw threaded on its upper end, as shown in Fig. 4. This tubular member is extended through a hole formed in the cowl 48 of the automobile and is held in position by nuts 49 which are screw threaded upon said member. Between the nuts and the cowl 48, the member is surrounded by tapered washers 50, of compressible material, having their tapered surfaces suitably formed to engage with the

5 cowl 48 and clamp the same securely when the nuts 49 are screwed into position. The tubular member 47 is also attached to the frame of the signal member and thus forms a rigid connection between said frame, the cylinder 46 and the cowl 48.

10 The piston 45 is reciprocated within the cylinder 46 by fluid under suction from the manifold of the engine cylinder through a suitable tubular connection 51, indicated in Fig. 1 and shown in part in Fig. 4. Whether the fluid shall be permitted to act above or below the piston is determined by the ball valves within the valve block 42; and the position of these balls is selectively controlled 15 from the levers 36, 37 within the car or from the brake pedal, as will be described.

20 The pipe 51 from the engine manifold connects with a bore 52 in the valve block 42, which bore extends downwardly within the block and connects with a horizontal bore 53. This bore 53 is projected into the block from the left hand side, as shown in Fig. 4, terminating at its right hand end in a similarly constructed manifold 54 adjacent the cylinder 46, said manifold 54 being best shown in Fig. 7. The outer end of each of these manifolds is closed by a suitable plug so as to make it air tight. Adjacent the plug 25 in the manifold 53, the latter connects with another manifold 55, which is best seen in Fig. 8, although it appears in dotted lines in Fig. 6. Extending downwardly from the upper surface of the valve block 42 are 30 four bores constituting valve chambers, the outer end of each of these bores being closed by suitable screw plugs. On that side of the block adjacent the cylinder 46 there are three of these valve chambers and screw plugs in 35 a row, as shown in Figs. 6 and 7. In the latter figure the valve chambers are designated 56, 57 and 58 and the screw plugs closing the latter are designated 59. These valve chambers are connected with one another 40 through manifold passages 60; and the center chamber 57 is connected with the top of the operating cylinder 46 through a fluid passage 61. The inner or lower ends of each of the valve chambers is conical, as shown, 45 to form seats for balls 62. When these balls rest upon the seats they close passages 63 leading to the manifold 54. When any one of these valves is lifted it establishes communication between pipe 51 and the space 50 above the piston 45 of the cylinder 46, whereby the piston is drawn upwardly to operate the signal, the piston being connected with the rack 29 through the piston rod 64. The rods 40, hereinbefore described, extend upwardly through the valve block beneath the balls in chambers 56 and 57, respectively, the said rods being suitably packed to prevent leakage by the glands 41, previously referred to. The ball 62 in the chamber 58 is not controlled by the hand levers 36, 37, but by the

brake pedal 65, shown in Fig. 22. In applying the brakes, this pedal is moved in the direction of the arrow. Connected to the pedal below its pivot 66, as at the point 67, is a yielding member 68 which leads to the 70 arm 69 of a bell crank which is pivoted at 70, the other arm 71 of the crank being connected to a rod 72 which extends upwardly into the valve block 42 beneath the ball 62 in the valve chamber 58. Therefore, when the brake lever 75 65 is operated, the bell crank is rocked to lift its rod 72 and its corresponding ball valve 62 to establish connection between the engine manifold and the upper end of the cylinder 46. Whereas the rods 40 operate their corresponding rods 44 to control the dogs 31, 31^a, thus to arrest the signaling member 20 to indicate the right and left-hand turns, the rod 72 has no corresponding rod 44, and when it lifts its ball valve 62 there is no dog 80 to arrest the movement of the signaling member, which continues its movement until it contacts with the frame 27 at the point 27^a in Fig. 4. When in this position against this contact point, the signaling member indicates 85 that the car is to stop.

90 It will thus be seen that, when any one of the ball valves 62 is lifted, the piston 45 is caused to rise to operate the signaling member to display a signal corresponding to the 95 particular ball valve that has been lifted.

99 In addition to the three valve chambers 56, 57 and 58, the block 42 is provided with a fourth valve chamber 73, the same having a ball valve 62^a therein. This valve is adapted to rest upon a seat like those of the other chambers and to be lifted by a rod 74 which corresponds in structure and arrangement with the rods 40. This ball valve 62^a controls a passage 75 which leads to the cylinder 46 at its lower end beneath the piston 45. Assuming that the piston has been raised within the cylinder, it is returned to the position shown in Fig. 4 by lifting the ball valve 62^a, which establishes suction from the engine manifold through the pipe 51, passage 52, manifolds 53 and 55 to the valve chamber 73 and thence, through the passage 75, to the cylinder 46, thus to draw down the piston and return the signaling arm to its neutral or concealed position. No matter which one of the ball valves 62 may be raised, the valve 62^a must, at the same time, be seated, as otherwise there would be a suction upon both ends of the cylinder. Conversely, whenever the valve 62^a is raised, 105 any valve 62 which had been lifted must be seated.

110 In order to obtain this alternate movement of the return valve 62^a and the operating valves 62, the rods 40 and 72 are caused to 115 rock a lever plate 76, which is pivoted on trunnions 77 at its ends, this plate being shown in plan in Fig. 23. As will be seen from the latter figure, the plate has three sets of prongs 78, 79 and 80 upon one of its 120 125 ends.

side edges and a single set of prongs 81 on its opposite side edge. This latter set of prongs straddles the rod 74, the latter being provided with conical nuts 82 on opposite sides of the prongs 81 so that the plate 76 causes the rod 74 to move up and down whenever the plate is rocked by either of the rods 40 or the rod 72. To facilitate the return of the plate 76 to its normal position, a spring 83 may be attached thereto, as indicated in Fig. 21.

From the description thus given it will be understood that, when it is desired to turn to the right hand, the operator lifts the lever 36 which simultaneously sets the dog 31^a into position for arresting the signaling member in its upwardly inclined position, shown in Fig. 1, and also lifts the valve 62 to establish communication between the engine manifold and the upper part of the cylinder 46. The same movement of the lever 36 rocks the lever plate 76 to lower the return valve 62^a so as to make the suction above the piston 45 effective. Having made the right hand turn, the operator returns the lever 36 to its normal position, thereby lowering the ball 62 which had been raised and rocking the lever plate 76 to raise the return valve 62^a, thereby establishing connection between the engine manifold and the bottom part of the cylinder 46 thus to draw the piston downwardly and restore the signal member to its neutral or invisible position. If the driver should next decide to turn to the left he operates the lever 37 with like effect and then returns it to normal position, which again restores the parts, as before described. If he should decide to stop the car and so applies his brake, he will rock the lever plate 76 to lower the ball valve 62^a and raise the valve in the chamber 58, thus to cause the piston to move upwardly. But in this case no dog has been set and the signaling member will continue to turn until it engages with the stop 27^a, as has been described. Upon the release of the brake pedal, the lever plate 76 is returned to normal which causes the piston to be drawn down to the bottom of the cylinder, thus to restore the signaling member to its neutral position.

Owing to the fact that brakes become worn, it becomes necessary to move the brake pedal different distances in setting the brakes. We have, therefore, provided the yielding connection 68 between the brake pedal and the bell crank 69. To prevent the bell crank from being rocked too far, we further provide a stop 84 to arrest the latter in a definite position irrespective of the variations in throw of the pedal.

In order to illuminate the sign, an electric current is supplied through a wire 85 which leads to the battery, not shown. This wire is extended upwardly in the casing of the signaling device and is connected, through

a binding post 86, with a spring contact 87, the latter having a metallic pin 88 which is pressed toward the left, as shown in Fig. 5. The position of the pin 88 is shown by the dotted circle 88 in Fig. 4, from which it will be seen that, when the parts are in their normal positions, the pin bears upon an insulated member 89 which is suitably mounted upon the adjacent segment 25^a, said member 89 appearing in side elevation in Fig. 17. Normally, therefore, this pin bears upon the member 89 of insulating material and no current can flow. Substantially as soon, however, as the gear segment 28 with the segmental element 25^a moves from its normal position, counter clock-wise as shown in Fig. 4, the metallic pin 88 moves off of the insulating member 89 and onto a conductor 90 which is suitably attached to the side of the element 25^a but is properly insulated therefrom, as will be clearly understood. The conductor 90 is bent about the shaft 26 and concentric therewith, so that, no matter how far the gear segment may turn, the pin 88 will remain in contact with this conductor. The latter is carried upwardly into the base portion 91 of the socket 92 of the lamp 20^c. This lamp is suitably grounded to the frame of the signaling device for the return of the current to the battery, as will be understood. Whenever, therefore, the signal member is turned from its normal or neutral position, the lamp 20^c is lighted to illuminate the signal which thus becomes effective for use in the darkness.

The piston 64 passes outwardly through a stuffing box 93 in the cylinder head 94. Extending through the head are a plurality of screws 95, the inner ends of which are threaded into a follower plate 96. By turning the said screws, this plate may be drawn toward the head 94 to compress packing 97 into the joint between the head and the cylinder walls. The follower plate supports the packing about the piston rod also, but this packing is compressed principally by screwing down on the nut of the stuffing box.

Having thus described our invention, what we claim as new and desire to secure by Letters Patent is:

1. A device of the character described comprising a signaling member, means connected with said member and adapted to move it into its farthest position to indicate a stop, an arresting element connected with and movable with the signaling member, a dog for engaging the said element, means under control of the operator for moving said dog into position to engage the said arresting element, and means operable upon the return of the dog to normal position for automatically returning the signaling member to its normal position.

2. A device of the character described comprising a signaling member, means connect-

ed with said member and adapted to move it into its farthest position to indicate a stop, an arresting element connected with and movable with the signaling member, a dog for engaging the said element, means under control of the operator for moving said dog into position to engage the said arresting element, means operable upon the return of the dog to normal position for automatically returning the signaling member to its normal position and means for illuminating said member while it is in any indicating position.

3. A device of the character described comprising a signaling member, means connected with said member and adapted to move it to its farthest position to indicate a stop, a pair of arresting elements connected with and movable with said member, a pair of dogs movable into position for engaging with the respective elements for arresting the movement of the signaling member in its intermediate positions, a pair of selective devices under control of the operator, connections between said devices and the respective dogs whereby the operator may select and operate either one of said dogs, and means under control of the selective devices for returning the signaling member to its normal position when the operated selective element is returned to its normal position.

4. A device of the character described comprising a signaling member, means connected with said member and adapted to move it to its farthest position to indicate a stop, a pair of arresting elements connected with and movable with said member, a pair of dogs movable into position for engaging with the respective elements for arresting the movement of the signaling member in its intermediate positions, a pair of selective devices under control of the operator, connections between said devices and the respective dogs whereby the operator may select and operate either one of said dogs, means under control of the selective devices for returning the signaling member to its normal position when the operated selective element is returned to its normal position, and means for illuminating said member while it is in any indicating position.

5. A device of the character described comprising a signaling member, a cylinder, a piston within said cylinder, connections between the piston and the said member for moving the latter from the piston, a source of fluid below atmospheric pressure, a valve block connected with said source and having passages therein for said fluid, connections between said passages and the said cylinder on opposite sides of the piston therein, setting valves in said block controlled by the operator for causing said fluid to move the piston and thus cause the signaling member to indicate intended right and left-hand turns and an intended stop, a return valve for causing the

fluid to return the piston and the said member to their normal positions, means for moving the setting valves selectively, and means controlled by the latter means for simultaneously moving the return valve, whereby, when any one of the setting valves is operated to set the signaling member the return valve is closed and when the latter valve is operated to return the signaling member the operated setting valve is closed.

6. A device of the character described comprising a signaling member, a cylinder, a piston within said cylinder, connections between the piston and the said member for moving the latter from the piston, a source of fluid below atmospheric pressure, a valve block connected with said source and having passages therein for said fluid, connections between said passages and the said cylinder on opposite sides of the piston therein, setting valves in said block controlled by the operator for causing said fluid to move the piston and thus cause the signaling member to indicate intended right and left-hand turns and an intended stop, a return valve for causing the fluid to return the piston and the said member to their normal positions, means for moving the setting valves selectively, means controlled by the latter means for simultaneously moving the return valve, whereby, when any one of the setting valves is operated to set the signaling member the return valve is closed and when the latter valve is operated to return the signaling member the operated setting valve is closed, and means for illuminating said signaling member while it is in any of its indicating positions.

7. A device of the character described comprising a signaling member, a cylinder, a piston within said cylinder, connections between the piston and the said member for moving the latter from the piston, a source of fluid below atmospheric pressure, a valve block connected with said source and having passages therein for said fluid, connections between said passages and the said cylinder on opposite sides of the piston therein, setting valves in said block controlled by the operator for causing said fluid to move the piston and thus cause the signaling member to indicate intended right and left-hand turns and an intended stop, a return valve for causing the fluid to return the piston and the said member to their normal positions, hand operated means for selectively moving certain of the setting valves to indicate intended right-hand and left-hand turns, a brake pedal, means controlled by the pedal for moving the other setting valve to cause the signaling device to indicate a stop, and means controlled by the hand operated means and the pedal for moving the return valve simultaneously with any one of the setting valves, whereby, when any one of the setting valves is operated to set the signaling member the

return valve is closed and when the latter valve is operated to return the signaling member the operated setting valve is closed.

8. A device of the character described comprising a signaling member, a cylinder, a piston within said cylinder, connections between the piston and the said member for moving the latter from the piston, a source of fluid below atmospheric pressure, a valve block connected with said source and having passages therein for said fluid, connections between said passages and the said cylinder on opposite sides of the piston therein, setting valves in said block controlled by the operator for causing said fluid to move the piston and thus cause the signaling member to indicate intended right and left-hand turns and an intended stop, a return valve for causing the fluid to return the piston and the said member to their normal positions, hand operated means for selectively moving certain of the setting valves to indicate intended right-hand and left-hand turns, a brake pedal, means controlled by the pedal for moving the other setting valve to cause the signaling device to indicate a stop, means controlled by the hand operated means and the pedal for moving the return valve simultaneously with any one of the setting valves, whereby, when any one of the setting valves is operated to set the signaling member the return valve is closed and when the latter valve is operated to return the signaling member the operated setting valve is closed, and means for illuminating said member while it is in any indicating position.

9. A device of the character described comprising a signaling member, a cylinder, a piston within said cylinder, connections between the piston and the said member for moving the latter from the piston, a source of fluid below atmospheric pressure, a valve block connected with said source and having passages therein for said fluid, connections between said passages and the said cylinder on opposite sides of the piston therein, setting valves in said block controlled by the operator for causing said fluid to move the piston and thus cause the signaling member to indicate intended right and left-hand turns and an intended stop, a return valve for causing the fluid to return the piston and the said member to their normal positions, means for moving the setting valve selectively, a rocking plate operated by the latter means, and a valve rod connected with the said rocking plate for moving the return valve in a direction opposite to the movement of the setting valves whereby, when any one of the setting valves is operated to set the signaling member the return valve is closed and when the latter valve is operated to return the signaling member the operated setting valve is closed.

65 10. A device of the character described

comprising a signaling member, a cylinder, a piston within said cylinder, connections between the piston and the said member for moving the latter from the piston, a source of fluid below atmospheric pressure, a valve block connected with said source and having passages therein for said fluid, connections between said passages and the said cylinder on opposite sides of the piston therein, setting valves in said block controlled by the operator for causing said fluid to move the piston and thus cause the signaling member to indicate intended right and left-hand turns and an intended stop, a return valve for causing the fluid to return the piston and the said member to their normal positions, means for moving the setting valve selectively, a rocking plate operated by the latter means, a valve rod connected with the said rocking plate for moving the return valve in a direction opposite to the movement of the setting valves whereby, when any one of the setting valves is operated to set the signaling member the return valve is closed and when the latter valve is operated to return the signaling member the operated setting valve is closed, and means for illuminating said signaling member while it is in any of its indicating positions.

11. The combination with an automotive vehicle having an upright post in front of and at the left of the driver, of a signaling member pivotally mounted upon said post, selective means movable by the operator of the vehicle for causing the said member to move to different positions to give different signals, and means movable upon the return movement of the selective means for causing the signaling member to return to its normal neutral position.

12. The combination with an automotive vehicle having an upright post in front of and at the left of the driver, of a signaling member pivotally mounted upon said post, selective means movable by the operator of the vehicle for causing the said member to move to different positions to give different signals, means movable upon the return movement of the selective means for causing the signaling member to return to its normal neutral position, and means for illuminating said member while it is in its signaling positions.

13. The combination with an automotive vehicle having a cowl and an upright post in front of and at the left of the driver, of a signaling member pivotally mounted on said post, a gear segment connected with said member, a rack operatively engaging said gear segment, a cylinder, a piston within said cylinder and connected with the said rack, means for connecting the said cylinder to the cowl of the vehicle, selective means movable by the operator for causing the piston in the cylinder to move in one direction to turn the

5 signaling member to different positions to give different signals, and means movable upon the return movement of the said selective means for causing the piston to move in its opposite direction thus to return the signaling member to its normal position.

10 14. The combination with an automotive vehicle having an intake manifold for the engine, of a signaling member, a cylinder, a piston within said cylinder, connections between the piston and the said member for moving the latter from the piston, a valve block connected with the engine manifold and having passages therein, connections between 15 said passages and the said cylinder on opposite sides of the piston therein, setting valves in said block controlled by the operator for causing said piston to move in one direction to set the signaling member to indicate intended right and left-hand turns and an intended 20 stop, a return valve in said block for causing the piston to move in the opposite direction thus to return the said member to its normal position, means for moving the setting valves selectively, and means controlled by the latter means for simultaneously moving the return valve, whereby, when any one 25 of the setting valves is operated to set the signaling member the return valve is closed and when the latter valve is operated to return the signaling member the operated setting valve is closed.

30 15. The combination with an automotive vehicle having an intake manifold for the engine, of a signaling member, a cylinder, a piston within said cylinder, connections between the piston and the said member for moving the latter from the piston, a valve block connected with the engine manifold and having passages therein, connections between 35 said passages and the said cylinder on opposite sides of the piston therein, setting valves in said block controlled by the operator for causing said piston to move in one direction to set the signaling member to indicate intended right and left-hand turns and an intended stop, a return valve in said block for causing the piston to move in the opposite direction thus to return the said member to its normal position, means for moving the setting valves selectively, and means controlled by the latter means for simultaneously moving the return valve, whereby, when any one 40 of the setting valves is operated to set the signaling member the return valve is closed and when the latter valve is operated to return the signaling member the operated setting valve is closed, and means for illuminating the signaling member while it is in any of its indicating positions.

45 16. A device of the character described comprising an elongated casing, a signaling member pivoted at its lower end within the lower part of the casing, means connected 50 with said member and adapted to move it to

its farthest position to indicate an intended stop, means for arresting said member in intermediate positions to indicate intended right and left-hand turns, selective devices under control of the operator for setting said 55 arresting means, thereby to determine the extent of movement of the signaling member, and means automatically operative upon the return of the selective devices to their normal positions to return the signaling member to its normal position.

60 17. A device of the character described comprising an elongated casing, a signaling member pivoted at its lower end within the lower part of the casing, means connected 65 with said member and adapted to move it to its farthest position to indicate an intended stop, means for arresting said member in intermediate position to indicate intended right and left-hand turns, selective devices under 70 control of the operator for setting said arresting means, thereby to determine the extent of movement of the signaling member, means automatically operative upon the return of the selective devices to their normal 75 positions to return the signaling member to its normal position, and means for illuminating said member while it is in any indicating position.

80 In testimony whereof we have signed our 85 names to this specification.

HENRY E. WHIPPLE.
FRANK P. MEEKER.
